(57) **CLAIM**

The ornamental appearance for a wheeled shovel, as shown and described.

DESCRIPTION

FIG. 1 is an upper perspective view of the wheeled shovel, showing our new design;

FIG. 2 is another upper perspective view of the wheeled shovel thereof;

FIG. 3 is a lower perspective view thereof;

FIG. 4 is another lower perspective view thereof;

FIG. 5 is a top plan view thereof;

FIG. 6 is a bottom plan view thereof;

FIG. 7 is a front elevation view thereof;

FIG. 8 is a rear elevation view thereof;

FIG. 9 is a right elevation view thereof; and,

FIG. 10 is a left elevation view thereof.

The details shown in broken lines are for illustrative purposes only and form no part of the claimed design.
